CLAIM

The ornamental design for a wall-mounted single-handle mixing faucet, as shown and described.

DESCRIPTION

FIG. 1 is a top, front, left-side elevational view of a wall-mounted single-handle mixing faucet showing my new design;

FIG. 2 is a front view thereof;

FIG. 3 is a top view thereof;

FIG. 4 is a bottom view thereof;

FIG. 5 is a left side elevational view thereof, the right side elevational view being mirror symmetrical thereto; and,

FIG. 6 is a bottom view thereof.
